THOMAS E. POPE, OF ALAMEDA, CALIFORNIA, ASSIGNOR TO LOUREY-POPE MANUFACTURING COMPANY, OF SAN FRANCISCO, CALIFORNIA, A CORPORATION.

EXPANSIBLE BIT.

988,143.

Specification of Letters Patent. Patented Mar. 28, 1911.

Application filed October 19, 1908. Serial No. 458,353.

To all whom it may concern:

Be it known that I, THOMAS E. POPE, a citizen of the United States, residing at Alameda, in the county of Alameda and State of California, have invented new and useful Improvements in Expansible Bits, of which the following is a specification.

The object of the present invention is to provide a bit which can be expanded while 10 the work is progressing to bore a recess or socket expanding inwardly. The utility of such a bit resides in the fact that a socket of this form is very advantageous for securing therein the end of a cylindrical bar, 15 rod, or other connection, as said end can be caused, by a wedge located centrally in the end of bar, or other connection, to spread and fill the socket thus formed, and thus make a firm and durable attachment of said 20 bar or other part in said socket. Furthermore, since a bit of this character can be used for boring holes of many different sizes, the number of tools required for boring holes of all sizes, is thereby reduced.

25 In the accompanying drawing, Figure 1 is a side view of a bit constructed in accordance with my invention; Fig. 2 is a cross section on the line 2—2 of Fig. 1; Fig. 3 is a broken longitudinal section 30 through the working end of the bit; Fig. 4 is a broken longitudinal section taken transversely of the cutter; Fig. 5 is an end view of the tube detached; Fig. 6 is a perspective view of the cutter detached.

35 Referring to the drawing, 1 indicates a cylindrical stem, adapted to be turned in the usual manner by a crank handle, not shown. At the power end the stem is screwed, as shown at 2, into a square shank 3, so that the latter can be detached, when desired, to remove the parts which normally surround the stem of the bit. The head 4 of the bit, at the working end of the stem, is formed with a central lead screw 40 5, and, above said lead screw with a transverse slideway 6, in which can slide a bit or cutter 7, which is formed with a lateral rib 8 sliding in a corresponding groove in one of the faces of the slideway 6. Fitting 45 closely around said stem is a tube 9, the lower end of which is enlarged and has formed, upon the face opposite to the cutter 7, a spiral rib 10, and the upper side of said cutter is formed with teeth 11 which 50 are engaged by said spiral rib 10. The result is that, if the bit stem rotates while the

tube is held stationary, the engagement of said teeth 11 with said spiral rib 10 causes the cutter to move outward in its slideway, and thus to enlarge the diameter of the 60 bore made by the cutter.

If it be desired that the hole should expand very rapidly as it increases in depth, it is only necessary to hold the tube 9 stationary during the whole time that the bit 65 is being turned, but, in making the teeth 11 sufficiently strong to resist the pressure upon the cutter, there is a minimum limit to the thickness which can be given to said teeth, and since for each complete turn of 70 the bit, the cutter is moved outward through a distance equal to the thickness of one tooth, a hole thus formed would generally expand too rapidly. To avoid this, the operator may from time to time release this 75 hold upon the tube, whereupon said tube will rotate with the bit, and the cutter will then not move outward. However, I herein show means whereby although the tube rotates as well as the bit, it does so at a 80 slower speed, whereby the hole does not expand too rapidly. For this purpose there is provided a frame 12 consisting of terminal rings 13, 14, and an intermediate ring 15, all connected by longitudinal bars 85 16. The ring 13 nearest the point of the bit has secured thereto a rubber ring 17 which is adapted to rest against the material in which the hole is to be bored and prevent the turning of said frame. Upon 90 the inner edges of the bars 16 are formed racks 18, which are engaged by the threaded outer edge of a disk 19, having a hub secured to the tube 9. Said frame thus constitutes a nut in which said disk turns. 95 The threaded portion 20 of the stem of the bit is screwed through the outer ring 14. The pitch of the threaded portion 20 of the stem is the same as that of the lead screw, so that, as the lead screw penetrates the hole, 100 the threaded portion 20 of the stem turns in the ring 14 without any tendency to move said ring and the whole frame 12 either to or away from the face of the object being bored. But the pitch of the thread of the 105 disk 19 is greater than that of the lead screw and of the threaded portion 20 of the stem, and the effect of this construction is to produce a rotation of the tube with the stem but at a slower speed. For, let it be 110 supposed, for brevity of description, that the bit is boring downward. Since the

tube is supported wholly by, and fits snugly on, the stem, it always rotates with the stem unless prevented from doing so by extraneous causes. Now the effect of the rotation of 5 the stem, and therefore also of the tube, is to move the lower sides of the threads of the disk out of contact with the faces in the rack teeth immediately below them, and to press the upper sides of said threads against the 10 under faces of the rack teeth immediately above them. If the pitch of the threads of the disk is the same as that of the stem threads, then this tendency, of the threads of the disk to press against the teeth above 15 them is balanced or neutralized by the fact that the stem, and therefore the disk, is also descending, at a rate corresponding to the pitch of the threads in both the disk and stem, and therefore also in the racks and in 20 the ring 14. But if, as in the present case, the pitch of the threads of the disk is greater than that of the stem, then the upward pressure of the upper sides of said threads against the teeth of the rack is not 25 so neutralized, but there is a resultant upward pressure. This pressure, by its friction upon the disk, retards the disk until the disk has, by the descent of the stem, also descended to such an extent that it no 30 longer presses upward against the teeth of the rack.

The action may be more readily understood by supposing that the several parts of the action take place in finite periods of 35 time instead of in infinitesimal periods. On such a supposition, the disk, rotating at the same speed as the stem, would first be arrested, by the upper sides of its threads impinging against the under sides of the rack 40 teeth immediately above. The stem however, is continually moving downward, and carries also the tube and disk downward, and therefore removes the upper sides of said threads from contact with the under 45 sides of said teeth. These parts being no longer in contact, the disk is again free to rotate with the stem, which it immediately does, but is again, as before, arrested by the upper sides of its threads impinging against 50 the under sides of the rack teeth immediately above, and so on. Of course, there is no such alternate or intermittent action, at any rate in periods of time perceptible to our observation, but the action, while practically continuous, is of the above-described 55 character.

An important feature of the invention consists in the construction whereby the stem and tube are entirely closed against the entrance of any borings and cuttings. While 60 the helical web is of great advantage in effecting the discharge of such cuttings from a hole bored by the cutter, even without this helical web my invention is superior to prior 65 forms of devices having an auger and a

cutter capable of being extended transversely, because, in all of these forms, so far as I am aware, the means for so extending the cutter transversely have necessitated openings or recesses, and especially openings 70 of variable size, into which the chips or cuttings can enter, and, thus accumulating in said openings, prevent the discharge of other chips and cuttings and greatly impair the efficiency and utility of the auger. In the 75 present invention, the tube fits snugly around the stem and leaves no cavities or passages for the entry and accumulation of the borings and cuttings.

It has already been stated that the three 80 racks are, in effect, a nut, within which the disk 19 on the tube turns. The threaded portion 20 of the stem and the ring 14, and the disk 19 and said racks, thus constitute a differential gear, producing a slow rearward 85 motion of the tube relatively to the stem.

While the differential gear herein shown is of the form shown for the purpose of enabling it to be operated automatically, by forming the nut for the screw of greater 90 pitch as a frame which engages the face of the material being penetrated, the invention is not limited to this specific construction.

I believe that I am the first to produce a relative motion of a cutter in an expandible 95 bit by means of a slow retardation of a tube around a sleeve effected by such differential gearing, and therefore I claim the invention as of a correspondingly broad scope, and that the nut used therewith may be of any 100 desired form.

By the word "nut" is meant the part having two dissimilar internal threads, which engage respectively the two screws, whether these threads be formed, as herein shown, by 105 the inwardly extending teeth of racks, or, in the usual manner, on the inside of a sleeve or tube.

It is advantageous that the tube have a loose engagement with the cutter, as that of the spiral rib on the end of the tube with the teeth on the upper side of the cutter, for this construction permits of a cutter being readily withdrawn and substituted by a new one.

I claim:—

1. An expandible bit comprising a stem, a cutter transversely movable in said stem, and a tube around the stem, said cutter being formed with teeth, and an end of the tube 112 being formed with a spiral rib engaging said teeth, substantially as described.

2. An expandible bit comprising a stem, a cutter transversely movable in said stem, a tube around the stem, said cutter being 11 formed with teeth, an end of the tube being formed with a spiral rib engaging said teeth, and a disk secured to the upper end of said tube, substantially as described.

3. An expandible bit comprising a stem, a 11

cutter transversely movable in said stem, a tube around the stem, said cutter being formed with teeth, and an end of the tube being formed with a spiral rib engaging said 5 teeth, said tube being rotatable with said stem, and means for rotating said tube with said stem but at a slower speed, substantially as described.

4. An auger bit comprising two elements, 10 a stem and a tube around said stem, one of said elements being formed with a transverse guide for a cutter, and a transversely movable cutter guided thereby and formed with teeth, an end of the other element being formed with a spiral rib engaging said 15 teeth to move the cutter transversely, substantially as described.

5. The combination of two elements, a stem and a tube around said stem, one of 20 said elements having an auger, a cutter movable transversely in a recess in said latter element, means for transversely moving said cutter, arranged to be actuated by the rotation, relative to said element, of the other 25 element, and means for producing such relative rotation, comprising two screws of different pitches, one on each element, and a nut having threads respectively engaged by said screws, substantially as described.

30 6. The combination of two elements, a stem, and a tube around said stem, an auger secured to one of said elements, a cutter movable transversely in a recess in said latter element, means for transversely moving 35 said cutter, arranged to be actuated by the retardation, relative to said element, of the other element, and means for producing such relative retardation, comprising two screws of different pitches, one on each element, and a nut having threads respectively engaged by said screws, substantially as described.

40 7. The combination of a stem, having an auger, a cutter movable transversely in a recess in said stem, and a device for transversely moving said cutter having threads of different pitches, the stem having a part engaging one of said threads, and an element, movable relatively to the stem and operatively connected with the cutter having a part engaging the other thread, substantially as described.

50 8. The combination of a stem, having an auger, a cutter movable transversely in a recess in said stem, and a device for transversely moving said cutter having threads of different pitches, the stem having a part engaging one of said threads, and an element, movable relatively to the stem and operatively connected with the cutter having a part engaging the other thread, said de-

vice being provided with means for automatically controlling its rotation, substantially as described.

9. The combination of two elements, a 65 stem and a tube rotatable around said stem, one of said elements having an auger and a transverse recess immediately above said auger, a cutter in the form of a bar free at both ends, fitting snugly in said recess and 70 slidable therein, and means actuated by the other element, and loosely engaging said cutter bar, for so sliding said cutter by the rotation of said latter element, substantially as described. 75

10. An auger bit comprising two elements, one fitting closely in the other, means for moving one of said elements relatively to the other, the other element having an auger and formed, adjacent to said auger and to 80 the end of the movable element, with a transverse guideway for a cutter, and a cutter bar, free at both ends and movable transversely therein, said cutter and the movable element having parts loosely co-engaging 85 each other so that from the movement of said latter element in either of two opposite directions, said cutter may be correspondingly moved transversely, substantially as described. 90

11. A bit having a stem and a transverse recess formed in the lower end of the bit, a transversely slidable cutter in said recess, a tube around said stem formed with a helical web, and an operative connection between 95 the lower end of said tube and said cutter, whereby when said tube is rotated on said stem, said cutter is moved transversely, substantially as described.

12. The combination of a bit-head, an extension arm guided therein and having a series of teeth, and a sleeve surrounding the shank of the bit and having an inclined portion to engage said arm, whereby rotation of said sleeve may move said arm end- 105 wise, substantially as described.

13. The combination with a bit of a cutting arm guided therein so as to be adjustable in or out laterally, and having a series of teeth, and a rotating adjuster arranged to 110 turn about an axis parallel or coincident with the axis of the bit, and having a spirally curved portion engaging the teeth of said arm, substantially as described.

In testimony whereof I have hereunto set 115 my hand in the presence of two subscribing witnesses.
